(57) **CLAIM**

We claim the ornamental design for the computing device holder, as shown and described.

DESCRIPTION

The present application is related to U.S. Design patent applications titled "Computing Device Dock" and "Computing Device Holder and Dock," each filed simultaneously here-with.

FIG. 1 is a perspective view of the computing device holder according to the invention;

FIG. 2 is a front view thereof;

FIG. 3 is a back view thereof;

FIG. 4 is a side view thereof;

FIG. 5 is a side view thereof;

FIG. 6 is a top view thereof; and,

FIG. 7 is a bottom view thereof.

The broken lines shown in the drawings represent portions of the computing device holder that form no part of the claimed design.
